E. A. CHRISTOPH.

WALL RACK.

APPLICATION FILED NOV. 20, 1908.

926,468.

Patented June 29, 1909.

UNITED STATES PATENT OFFICE.

EMIL A. CHRISTOPH, OF CHICAGO, ILLINOIS.

WALL-RACK.

No. 926,468.

Specification of Letters Patent.

Patented June 29, 1909.

Application filed November 20, 1908. Serial No. 463,705.

To all whom it may concern:

Be it known that I, EMIL A. CHRISTOPH, a citizen of the United States, and a resident of Chicago, in the county of Cook and State 5 of Illinois, have invented certain new and useful Improvements in Wall - Racks, of which the following is a full, clear, and exact description.

My invention relates to wall-racks such as 10 are adapted to be used in a kitchen, pantry, or the like, wherein it is desirable to place a number of handy and much-used dishes, or pans, and on which utensils such as cups, spoons, egg-beaters, and the like may be 15 hung.

The object of my invention is to construct such a device entirely out of sheet-metal in order to prevent the same wearing out, and which, by stamping said metal out in its 20 proper shape, can be economically made up into a rack by simply riveting the several parts thereof together.

Another object is to provide a wall-rack that is strong and durable, and which, when 25 placed on the wall, will, owing to its peculiar construction, be firmly and rigidly held in place without the necessity of using outside braces or stays.

This I accomplish by the means and in the 30 manner hereinafter fully described and as more particularly pointed out in the claims.

In the drawings:—Figure 1 is a perspective view of one of my improved racks mounted on a wall. Fig. 2 is a transverse vertical 35 section thereon, taken on dotted line 2—2, Fig. 1, and drawn to an enlarged scale.

Referring to the drawings, it will be seen that my improved rack comprises a pair of 40 oppositely arranged wedge, or V-shaped metal wall-brackets A, A, (substantially Z-shaped in cross-section) having the lateral flanges of their rear portions in substantially the same vertical plane as the wall or other supporting means to which they are secured.

45 The connecting web between the rear and forward flanges of these brackets is disposed at right angles to the supporting means in a vertical plane and its outer edge preferably tapered downwardly in a V-shape until it 50 meets said rear flange, while the outer flange is bent laterally at substantially right angles thereto. These wall-brackets are preferably placed a suitable distance apart, say about two feet, and are connected by means of several horizontally disposed parallel metal rails

or retaining strips B, B, and C. These retaining strips are preferably three in number and are riveted or otherwise suitably secured together at their ends to the outer flanges of the wall-brackets A, A. The lower one, C, 60 of these strips is preferably secured to the lowermost end of the outer flange of the wall-brackets, and it is provided with a plurality of substantially L-shaped hooks D, D, stamped out therefrom and bent upwardly. 65 These hooks are adapted to be used as hangers for such utensils as cups, spoons, beaters, and the like, that are usually provided with means whereby they may be hung pendent thereon. Riveted or otherwise 70 secured transversely across the central portion of these retaining strips B, B, and C, is a suitable transversely disposed metal tie-bar E, that is preferably slightly longer than the distance between the top edge of the 75 upper retaining-strip B and the bottom edge of the lower retaining-strip C, and the portion e thereof that extends below said lower rail C is bent obtusely to itself and projects downwardly in a plane parallel to the wall or other supporting means for the rack. Suitable screw-holes a, a, a, are tapped through the rear vertical flange of the wall-brackets and through the lower extension e of the tie-bar, by means of which the rack is 80 adapted to be securely held in place. Thus it will be seen that, after the wall-rack is secured in place the rear flanges of the wall-brackets A, A, will fit flush against the wall and the extension e of the tie-bar will 85 successfully prevent the bulging or spreading of the longitudinal retaining-strips B, B, and C.

If desired, after the rack has been assembled and riveted together, it may be given a 95 thick coat of lacquer or enamel to prevent the corrosion of the sheet-metal of which it is formed, or, in order to give the rack a neat appearance, it may be nickel-plated by any well-known process.

100 What I claim as new is:—

1. A wall rack comprising sheet-metal wall brackets of inverted acute angular shape the rear vertical edges of which are secured to the wall and the forward inclined edges of 105 which are flanged transversely, and horizontal retaining-strips secured to said flanges and connecting said brackets, the lowermost of said retaining strips being provided with a plurality of upturned hooks.

110

2. A wall rack comprising sheet-metal wall brackets of inverted acute angular shape the rear vertical edges of which are secured to the wall and the forward inclined edges of which are flanged transversely, and parallel sheet-metal retaining strips secured to said flanges and connecting said brackets, the lowermost of said retaining strips being provided with a plurality of punched out integral hooks.
3. A wall rack comprising sheet-metal wall brackets of inverted acute angular shape the rear vertical edges of which are secured to the wall and the forward inclined edges of which are flanged transversely, horizontal retaining strips secured to said flanges and connecting said brackets, the lowermost of said retaining strips being provided with a plurality of upturned hooks, and a tie-rail secured to said retaining strips mediate said brackets.
4. A wall rack comprising sheet-metal wall brackets of inverted acute angular shape the rear vertical edges of which are secured to the wall and the forward inclined edges of which are flanged transversely, horizontal retaining strips secured to said flanges and connecting said brackets, the lowermost of said retaining strips being provided with a plurality of upturned hooks, and a tie-rail secured to said retaining strips mediate said brackets and is provided with an angularly

disposed portion that extends below the lower retaining-strip.

5. A wall rack comprising sheet-metal wall brackets of inverted acute angular shape the rear vertical edges and the forward inclined edges of which are flanged transversely, and horizontal retaining strips secured to said forward flanges and connecting said brackets, the lowermost of said retaining strips being provided with a plurality of upturned hooks.

6. A wall rack comprising sheet-metal wall brackets of inverted acute angular shape the rear vertical edges of which are secured to the wall and the forward inclined edges of which are flanged transversely, parallel sheet-metal retaining strips secured to said flanges and connecting said brackets, the lowermost of said retaining strips being provided with a plurality of punched out integral hooks and a sheet-metal tie-rail secured to said retaining strips mediate said brackets and is provided with an angularly disposed portion that extends below the lower retaining strip and is secured to the wall.

In testimony whereof I have hereunto set my hand and seal this 14th day of November, A. D., 1908.

EMIL A. CHRISTOPH. [L. s.]
